D. W. Henderson,

Stump Elevator.

11031,386.

Patented Feb. 12, 1861.

UNITED STATES PATENT OFFICE.

DANIEL W. HENDERSON, OF DEERFIELD, PENNSYLVANIA.

STUMP-MACHINE.

Specification of Letters Patent No. 31,386, dated February 12, 1861.

To all whom it may concern:

Be it known that I, DANIEL WEBSTER HENDERSON, of Deerfield, in the county of Warren, in the State of Pennsylvania, have 5 invented a new and Improved Stump-Machine; and I do hereby declare that the following is a full and exact description of the same, reference being had to the accompanying drawings and the characters of reference 10 marked thereon.

Figure 1 represents my machine with all its parts adjusted in working order.

A, A, are strong upright posts well braced and set on a shoe or runners as shown in 15 drawing. Y is a cross piece, B B two ties connecting A A with the three upright posts C, C, C. These posts C C C stand on a foot D and are securely bound together by the cross piece X. This constitutes the 20 frame of my machine.

E, F, are levers resting on an iron fulcrum at, Y.

u is a pulley on the long end of the lever, E, over this pulley runs a cord or rope M, M, 25 M, M, one end of this rope is fastened at 13 on one of the posts, C, it then passes over the pulley u then down under the pulley s and over the shaft of the wheel and axle 14.

a' a' is a shorter rope attached to the long 30 ends of the levers E, F, passing over the pulley W on cross piece X by means of this rope when the lever E is drawn down, F, is lifted up.

P, P, is another rope similar to M, M, 35 M, M, on the lever F passing over the pulley T, and on the roller 14 exactly like M, M, M, M, only with this difference i. e., P P passes over the roller 14 and M, M, M, M, under the same, and by this arrangement it 40 is evident that on turning the roller 14 in one direction the rope M M M M is wound up and P P unwound thus drawing down the lever E and drawing up the lever F, and by reversing the motion of 14 the contrary result is produced.

On the roller 14 are two drum wheels H, and G. On these wheels the ropes N, N, N, and O, O, O, are wound in opposite directions as are the ropes M M M M and P, P.

50 To these ropes horses may be hitched when desired. By this construction the machine may be used by "hand power" applied to

the cranks s' s' or "horse power" by attaching teams to the ropes O O and N N.

K is a bar of iron with slots 1, 2, 3, 4, 5 55 in it. On the lower end are hooks L to hook onto the roots of stumps; on the short end of the levers E and F are hooks one of which is shown v Fig. 1 and both of them v, 8, Fig. 2. These hooks have eye bolts on their 60 upper end which pass through the levers and are fastened with a nut and screw. See z z Fig. 1.

Fig. 2 better shows the hooks. K is the bar of iron with the slots (1 2 3 4 5 Fig. 1') 65 in it. v, 8, are the hooks of iron, 9, 10, are slides attached to hooks v, 8, and through which K passes. 6, 7, are springs attached to slides 9, 10, which throw the hooks into the slots 1, 2, 3, 4, 5. 70

The machine operates as follows to wit, when the hooks L are placed under the roots of a stump and the crank s' is turned and the rope M M M M wound up. The long end of the lever E is drawn down. The hook v 75 is now in slot 4. This of course draws K up and pulls on the stump at the same time the long end of the lever F is going up as before described, and the hook 8 (Fig. 2) on its short end is getting ready to pass into 80 slot 3 in K as soon as it shall reach it. When this is done the motion of the crank s' is reversed and F goes down as E did and this is continued until the bar K is drawn up to the last slot and the stump is thereby 85 "raised."

What I claim as my invention and desire to secure by Letters Patent of the United States is—

1. The construction of the bar K in combination with the hooks v, 8, constructed and combined as described. 90

2. Connecting the levers E and F together by the cord a' a', the same operated by means of the combination of the cords M, M, 95 M, M P, P, N N N, O O O, the pulleys U, S, T, W, and the wheel and axle 14 G, H, when the same are constructed in the aforesaid combination and for the purposes set forth.

DANIEL WEBSTER HENDERSON.
